TO AZADE DUVAL, OF MANCHESTER, NEW HAMPSHIRE.

TRANSFERRING MECHANISM FOR AUTOMATIC FILLING-REPLENISHING LOOMS.

1,417,541.

Specification of Letters Patent. Patented May 30, 1922.

Application filed May 22, 1920. Serial No. 383,429.

To all whom it may concern:

Be it known that I, EVARISTE MARTIN, a citizen of the United States, residing at Manchester, in the county of Hillsborough 5 and State of New Hampshire, have invented certain new and useful Improvements in Transferring Mechanism for Automatic Filling-Replenishing Looms, of which the following is a specification.

10 This invention relates to the transferrer of looms provided with automatic filling replenishing mechanism. In such looms, the supply of fresh filling carriers, such as bobbins, is maintained in a feeder or hopper; 15 and when call comes for replenishment, a transferrer, which is generally pivoted, is moved downwardly and acts to transfer a fresh filling carrier, such as a full bobbin, from the hopper into the shuttle, which is 20 then beneath the hopper on the lay. The transferrer usually contacts with the butt of the filling carrier, and sometimes also with a point at or adjacent to the tip, or at some intermediate point on the filling, but the 25 main force applied by the transferrer is to the butt.

My invention can be used in connection with the transferrer mechanism on looms of the Northrop type, or on any loom which 30 contains a bobbin magazine.

With most of such looms the head of the bobbin is squared and must fit in between guides or springs in the shuttle. If, in the process of transferring, the butt of the bobbin is turned, as frequently happens, by the 35 action of the transferring mechanism, the guides or springs in the shuttles are broken, or the head of the bobbin is broken and much damage occurs.

40 With force applied only to the butt, the tip end of the bobbin, not being held nor steadied, tends to swing out of position, and with all top or intermediate guides now in use, which do not grip and hold firmly the 45 bobbin, there is a strong tendency to turn or swing out of alignment, causing smashes and other damage.

As the filled bobbin occupies most of the width of the bobbin slot in the shuttle, there 50 is little room to pass down on each side until the winding cone at or near the tip end of the bobbin is reached. As the yarn is held

in such position that it runs from this point up over the exposed wooden tip of the bobbin, any tip guide or transferrer which engages the wood of the bobbin at the tip is 55 likely to cut the yarn.

My device consists of grippers which automatically seize the filling of the new bobbin, preferably midway on the winding cone, 60 near the tip end of the filling carrier where the yarn itself provides a suitable padding, thus doing away with the need of springs or other padding, and holds this part of the bobbin firmly in position as the transferring 65 mechanism descends, but the moment it begins to be withdrawn releases the bobbin. This gripping action prevents the bobbin from turning, swinging, pulling out, or getting out of true. It will work as well on 70 bobbins with round heads as those which are squared, and if located above the cone, it will not cut the yarn and will have sufficient room to operate.

It is obvious that to properly guide the 75 filling carrier or bobbin, the part of the arm which engages the tip or free end must strike at almost exactly the same time that the head is struck, as otherwise the tendency of the tip to kick up is not avoided. It is 80 also obvious that unless the tip is gripped by grippers, the tendency of the tip of the bobbin to kick down is not prevented and the tendency to turn on its axis is not prevented.

An important feature of my invention is 85 the axial adjustment of the shaft which supports the tip guide or grippers with reference to the head operating on the butt of the filling carrier, because by moving this tip guide axially it can be made to strike exactly the 90 point on the cone wind desired, and I claim to be the first to provide this axial adjustment of a tip guide adapted to engage a conical part of the filling wind. More particularly I claim to be the first to provide 95 grippers for a tip guide, especially in combination with an axial adjustment whereby these can be very accurately set so that they can work automatically by means of a closing finger at exactly the right moment and 100 will still have space to properly function.

The drawings illustrate so much of the mechanism of an ordinary filling replenishing loom, and the preferred form of inven-

tion embodied therein, as is necessary for the disclosure of said invention.

In the drawings, Fig. 1 is a side elevation, preferably in cross section, of the hopper stand, hopper, transerrer, and immediate connected parts of a loom of the well known Northrop type. Fig. 2 is a rear elevation, as from the right of Fig. 1, of a transerrer with my invention in position. Fig. 3 is a side elevation of the transerrer as shown in Fig. 2, both Figs. 2 and 3 showing the grippers as about to engage a bobbin, and Fig. 4 is a view similar to Fig. 3 showing the grippers engaging the bobbin. Fig. 5 is a plan view of a shuttle showing the guides, springs, and squared head bobbin. Fig. 6 is a side elevation, and Fig. 7 an end elevation of a bobbin with a squared head, of the type generally used in such looms.

Since this invention relates solely to the transerrer, it is unnecessary to illustrate or to describe in detail the automatic filling replenishing loom of which it forms a part and of which the construction and operation is familiar to those skilled in the weaving art.

For convenience of illustration, there is herein shown the hopper stand 1 from which rises the hopper 2 and upon which are rotarily mounted the discs, one of which 3 is shown. The disc 3 is provided with peripheral seats 4 in which are mounted the butts of the supply of fresh filling carriers B while the tips are mounted or supported in the opposite disc not illustrated.

The filling carrier to be transferred is brought by the rotation of the hopper into contact with the abutment 6 and in this position is held in the hopper by the yielding bobbin support 7. When the running filling breaks or becomes entirely or partially exhausted and filling replenishment is called for, mechanisms are set into operation which cause the transfer of this filling carrier resting against the abutment 6 from the hopper downwardly into the shuttle which is then on the lay and beneath the hopper, the spent filling carrier being simultaneously ejected.

The immediate instrumentality concerned in the transfer is the so-called transerrer 50 which is herein shown as pivotally mounted at 8 on the hopper stand, and of the shape of a bell crank lever. The transerrer projects between the discs of the hopper and in its normal inactive position the head 9 of the transerrer extends directly above the butt of the filling carrier in position for transfer.

S is a shuttle of well known type, with bobbin springs 31, butt guides 32 and bobbin slot 33, while B is the bobbin having the usual rings 30 and with its butt end squared at 10.

In the construction illustrated as embodying the present invention, the head 9 of the transerrer has extending laterally there-

from in a direction parallel with the filling carrier to a point opposite or nearly opposite the tip 13, the shaft 20.

This is shown as attached to head 9 by means of nuts such as 19.

At or near the end of shaft 20 are the grippers, indicated generally by G, preferably in a position midway above above winding cone 13, at the tip end of the filling carrier. They may engage the yarn mass Y on bobbin B at the large part 14, but the space between the yarn, as 14, and each side of the bobbin slot 33 in a shuttle, such as S, is rather small, and besides, the leverage is better the nearer the end of the bobbin the grippers are placed.

As shown, the grippers G comprise a stop 40, fixed arm 42, movable arm 43 and spring 45. The stop 40 includes a body adjustably fixed to shaft 20 by means of set screw 41, and a finger 46 which extends out toward the tip of shaft 20. The fixed arm 42 is shown as carried by the squared end 39 of shaft 20, and as terminating at the bottom in a fixed jaw or finger 51, and as having a curved portion 50 adapted to contact with the top of the yarn mass on the bobbin. This fixed arm and body 51 may be adjusted by turning shaft 20 by means of the nuts 19.

The pivoted arm 43 terminates at the bottom in a movable jaw 52, and has a closing finger 53 in position to engage the top of the filling carrier when the head and shaft descend to transfer the filling. Movable arm 43 also has at the top an extension 44 into which passes a spring 45, which is fixed at the other end to shaft 20 and tends to force extension 44 against stop 46, thus normally separating the movable jaw from the fixed jaw.

As the transferring mechanism descends, the jaws automatically close firmly on the filling and hold it and the bobbin from turning until the downward movement ceases. When the transferring mechanism, including the grippers, are withdrawn, the grippers automatically release the yarn mass or filling on the bobbin.

In case the grippers should not function properly, or in case spring 45 should break, the fixed arm 42 will still function and, if located midway on the winding cone 13, will act to better advantage than if it was on the large part of the yarn mass 14 or the wooden part of the tip 12.

I claim:

1. In a transferring mechanism for automatic filling replenishing looms, the combination of a head operating on the butt of the filling carrier, with a shaft carried thereby extending from said head parallel with the filling carrier to a point opposite the tip thereof, and grippers carried by the shaft comprising a downwardly extending arm fixed to the shaft and terminating in a

- fixed jaw in position to enter the shuttle and to engage the filling midway on the winding cone at the tip end of the filling carrier, a movable arm pivoted to the shaft 5 adjoining the fixed arm and terminating in a movable jaw in position to enter the shuttle and having a closing finger in position to engage the top of the filling carrier when the head and shaft descend to transfer the 10 filling, so located and of such shape that as the grippers descend it will engage the filling carrier and close the movable jaw on the fixed jaw, thereby gripping the filling on the filling carrier near the tip and holding 15 the filling carrier firmly in position until the head and shaft are withdrawn, together with a spring adapted to normally separate the movable jaw from the fixed jaw.
- 20 2. In a transferring mechanism for automatic filling replenishing looms, the combination of a head operating on the butt of the filling carrier, with a shaft carried thereby extending from said head parallel 25 with the filling carrier to a point opposite the tip thereof, and grippers carried by the shaft comprising a downwardly extending arm fixed to the shaft and terminating in a fixed jaw in position to enter the shuttle 30 and to engage the filling near the tip of the carrier, a movable arm pivoted to the shaft adjoining the fixed arm and terminating in a movable jaw in position to enter the shuttle and having a closing finger in position 35 to engage the top of the filling carrier when the head and shaft descend to transfer the filling, so located and of such shape that as the grippers descend it will engage the filling carrier and close the movable jaw on the fixed jaw, thereby gripping the filling or the filling carrier near the tip and holding the filling carrier firmly in position until the head and shaft are withdrawn, together with a spring adapted to normally 40 separate the movable jaw from the fixed jaw.
- 45 3. In a transferring mechanism for automatic filling replenishing looms, the combination with a shaft, of grippers carried by
- the shaft comprising a downwardly extending arm fixed to the shaft and terminating in a fixed jaw, a movable arm pivoted to the shaft adjoining the fixed arm and terminating in a movable jaw and having a closing finger in position to engage the filling carrier when the grippers contact therewith and to close the movable jaw on the fixed jaw, thereby gripping the filling carrier, together with a spring adapted to normally 50 separate the movable jaw from the fixed jaw.
- 55 4. In a transferring mechanism for automatic filling replenishing looms, the combination of a head operating on the butt of the filling carrier, with an axially adjustable shaft carried thereby extending from said head parallel with the filling carrier to a point opposite the tip thereof and grippers carried by the shaft automatically operable, and in position to engage the filling midway on the winding cone at the tip end of the filling carrier to grip the filling and prevent the filling carrier from turning.
- 60 5. In a transferring mechanism for automatic filling replenishing looms, the combination of a head operating on the butt of the filling carrier, with an axially adjustable shaft carried thereby extending from said head parallel with the filling carrier to a point opposite the tip thereof, and a tip 65 guide carried by the shaft in position to engage the filling midway on the winding cone at the tip end of the filling carrier.
- 70 6. In a transferring mechanism for automatic filling replenishing looms, the combination of a head operating on the butt of the filling carrier, with a shaft carried thereby extending from said head parallel with the filling carrier to a point opposite the tip thereof, and grippers carried by the shaft 75 automatically operable to grip the filling and prevent it from turning.
- 80 85 90

In testimony whereof I have affixed my signature.

EVARISTE MARTIN.
